UNITED STATES PATENT OFFICE.

JAMES F. ROWLEY, OF CHICAGO, ILLINOIS.

MATRIX FOR STUMP LEGS.

1,404,896.

Specification of Letters Patent. Patented Jan. 31, 1922.

Application filed March 28, 1921. Serial No. 456,270.

To all whom it may concern:

Be it known that I, JAMES F. ROWLEY, a citizen of the United States of America, and a resident of Chicago, county of Cook, and 5 State of Illinois, have invented certain new and useful Improvements in Matrices for Stump Legs, of which the following is a specification.

This invention relates mainly to a new 10 method of taking an impression of a stump by utilizing the weight of the patient to attain the pressure required and in the right direction for forming a matrix corresponding to the walking shape of the stump leg. 15 Heretofore it has been customary to form the matrix by placing plastic material around the stump and, therefore, the matrix did not correspond to the walking form, and made necessary building up the cast 20 taken from the matrix at points corresponding to the sensitive parts of the stump leg so as to relieve these parts of the leg from pressure when in the socket. A wholly accurate and comfortable fit was impossible 25 by such methods. The present invention relates to the discovery that if the matrix is made when the surfaces of the stump leg are under pressure as produced by the patient's weight, the soft parts of the stump 30 are displaced upwardly longitudinally of the stump leg to exactly the form assumed under walking conditions. This method overcomes the errors of prior systems of making artificial legs from measurements which 35 depended strongly on guess work as to just what to do and what not to do in the way of building up or cutting away parts of the cast on which the socket is formed.

The objects of the invention may be attained by the use of a structure such as 40 illustrated in the drawings, wherein—

Figure 1 illustrates a suspended matrix receiving an impression.

Fig. 2 is a fragmentary plan view of the 45 matrix.

Prior systems of fitting stump legs include such as are based on the use of templates made from measurements so that an approximate fitting might be had in a socket 50 carefully made in keeping with a template. However, sockets made by this method by the best workmen seldom attain the finest detail which makes a comfortable fitting artificial leg. The customary method of 55 forming a plaster Paris cast results in a cast accurately representing the formation

of the stump when in repose, but does not correspond with the real formation when the soft part or flesh is displaced by putting one's weight on the bearing portions of the 60 stump leg, and this method of making sockets invariably required a reduction in size of the cast by cutting it down or scraping it and by pasting on pieces of leather to make more room for bones in the socket. By 65 means of the present method, the matrix being formed with nearly or quite the weight of the patient on the matrix, the matrix when filled with plaster Paris produces a 70 cast which is identical in form with the 75 stump leg when in use. A wax socket reinforcement is built over this cast and afterward carefully fitted into the top of the artificial leg with the result that the socket is invariably a comfortable fit.

In carrying the present method into effect, use is made of a matrix of suitable length which has been laced to substantially the diameter of the stump leg. This matrix is made of one layer of light material such as cordovan and is more or less saturated 80 with a wax-like material and previous to the fitting of the matrix is warmed so as to become freely pliable and soft. This matrix is suspended by means of cords as illustrated 85 in Figure 1 of the drawing. The ends of the cords are tied to the matrix by passing the same through eyes 2 in the ears 3 formed at the sides of the upper end of the matrix 1. These ears are preferably backed by metal 90 plates 4 in order to hold the eyes 2 properly spaced. The upper ends of the cords 5 may be attached to any suitable support such as the backs of two chairs. While the matrix 95 is warm, the patient makes the impression as desired by lowering the stump leg into the matrix and placing more or less of his weight thereon. This causes the stump leg to assume its walking shape, the soft parts of the stump being pushed upwardly by the 100 pressure applied in the matrix. Since the matrix yields readily under the pressure, it assumes the walking shape of the stump leg. The matrix becomes rigid when its temperature is reduced to normal. The plaster cast 105 may then be made which without building up is suitable for use in forming the socket which is finally fitted to the artificial limb.

Although but one specific embodiment of this invention has been herein shown and described it will be understood that numerous details of the construction shown may be

altered or omitted without departing from the spirit of this invention as defined by the following claim.

I claim:

- 5 A matrix for obtaining the form of a stump leg under pressure consisting of a hollow cylindrical body formed of a layer

of flexible material like leather affording tensile strength in combination with a substance rendering the structure plastic only 10 when warmed.

Signed at Chicago this 25th day of March, 1921.

JAMES F. ROWLEY.
